IVAN J. NELSON
INVENTOR

BY
Geo. B. Wilcox
ATTORNEY

UNITED STATES PATENT OFFICE.

IVAN J. NELSON, OF SAGINAW, MICHIGAN.

SOAP-DISPENSING MACHINE.

Application filed September 24, 1923. Serial No. 664,529.

To all whom it may concern:

Be it known that I, IVAN J. NELSON, a citizen of the United States, residing at Saginaw, in the county of Saginaw and State of Michigan, have invented certain new and useful Improvements in Soap-Dispensing Machines; and I do hereby declare the following to be a full, clear, and exact description of the invention, such as will enable others skilled in the art to which it appertains to make and use the same.

This invention relates soap dispensing machines and the improvement pertains more particularly to an improvement in the means for cutting the soap and for feeding the soap to the cutters. The improvement also includes means to prevent the user from cutting an excessive amount of soap at a time, this device consisting in a mechanism that stops the operating handle after the cutter has made say, one revolution, requiring the operator to press a button on the side of the machine before the handle can again be turned to operate the cutter.

With the foregoing and certain other objects in view which will appear later in the specifications, my improvement consists in the devices described and claimed and the equivalents thereof.

In the drawings Fig. 1 is a part vertical section of a soap dispensing machine embodying my improvements.

Fig. 2 is a horizontal section on the line 2—2 of Fig. 1.

As is clearly shown in the drawings the soap dispensing machine consists in a receptacle consisting of an upper part 1 and a lower conical part 2. Rotatably mounted in the lower conical part is a revolvable cutter 3 which is preferably dished or cone shaped, the cutter having internal knife edges 4 and having an annular rim 5 at its large diameter, the lower face 6 of the rim comprising a circular guideway upon which the cutter rotates. The upper face 7 is formed with teeth meshing with a gear 8 which is operated by a crank 9.

Within the upper part 1 of the receptacle is a longitudinally movable spring pressed plunger 10, the bottom face of which is formed with camlike projections 11 adapted to engage the ends of the cakes of soap in the usual manner.

The plunger 10 is pressed downward by a pair of spirally tapered springs 12 and 13,

the springs being oppositely directed and separated by a vertically movable washer 14.

Washer 14 and the plunger 10 are both slidable on a fixed bar 15 secured axially in the upper part 1 of the receptacle, the bar 15 being in effect a non-rotatable central shaft that projects down into the conical cutter 3, as shown in Fig. 1.

The central non-revolvable bar 15 is preferably of square or other angular or equivalent cross section, and is adapted to receive the cakes of soap, which are formed with similar shaped axial openings.

The lower end of the bar 15 projects centrally part way into the conical revolvable cutter 3, as shown in Fig. 1. The purpose of this combination, viz., the central non-revolvable bar of angular or equivalent section and the revolvable conical cutter is to prevent the cakes of soap from turning while being fed down into the cutter.

Moreover, the lower end of the bar, projecting part way into the cutter, reinforces the thin tapered walls of the lower end of the cake while this lower end is being shaved away by the revolving cutter, thereby preventing crumbling of the lowermost edges.

The oppositely directed tapered springs 12 and 13 are capable of being compressed into small space and by reason of their shape produce a practically uniform pressure upon plunger 10 at both extremities of its travel.

By turning crank 9 the conical cutter 3 rotates and shaves the soap from the lower ends of the cakes that are yieldingly pressed against the cutter knives by the plunger 10.

The turning force is applied to the periphery of the cutter 3, and the periphery itself is guided and supported by the large bearing surface 6 so that the cutter remains in alignment while being driven by the gear 7 and handle 9 without danger of binding, since the cutter is entirely independent of shaft 15.

To prevent the user from turning crank 9 after he has secured a predetermined amount of shaved soap, I provide the cam and latch device which will now be described. Upon the periphery of rim 5 I provide a stop 16 and a cam 17 spaced apart as shown in Fig. 2. In the lower part 2 of the receptacle I provide a horizontal groove 18 in which slides a latch 19. This latch may be moved

toward or from the rim 5 so as to engage or be released from the stop 16. I also provide a push button 20 which is connected to latch 19 by a bar 21 pivoted as at 22 to the lower part 2 of the receptacle.

When latch 19 is out the cutter 3 is free to turn, but at that time the inner end of the stem of push button 20 is in the path of cam 17 on the rim of cutter 3. When cam 17 contacts with the stem of push button 20 it forces it outward, thus by means of bar 21 bringing latch 19 into the path of stop 16 on rim 5. Consequently only one revolution of cutter 3, equivalent to, say, two turns 15 of the crank 9, can be made without the cutter automatically locking itself. The operator must then push in the button 20 to release latch 19 before he can again turn the handle and dispense more soap.

As an article of manufacture the device above described is simple and relatively inexpensive. The upper part 1 of the receptacle, the lower part 2 and the cutter 3 with its toothed face 7 are preferably formed each 25 of a single casting.

The direct connection between the cutter 3 and gear 8 is such that the handle 9 may be safely turned with considerable force without danger either of breaking the cake of soap or injuring the machine, yet only a single turn of the cutter is possible without automatically locking the machine and requiring the operator to again push the button 20.

To lock the upper compartment 1 and the conical lower part 2 together in their assembled relation I preferably provide a socket-headed set screw 23 threaded into a boss on the part 2 taking against the rim of the upper compartment, as shown in Fig. 1.

Having thus described my invention, what I claim and desire to secure by Letters Patent is:

1. In a soap dispensing machine, the combination of a receptacle for the soap to be dispensed, a revolvable dished cutter receiving the soap, means for revolving said cutter and a movable latch carried by said receptacle and engaging said cutter at each revolution and means for manually releasing 45 said latch.

2. In a soap dispensing machine, the combination of a receptacle for the soap to be dispensed, a revolvable dished cutter receiving the soap, means for revolving said cutter, cam-stops on said cutter, and a movable latch carried by said receptacle and engaging said stops at each revolution of the cutter, and manual releasing means for said latch.

3. In a soap dispensing machine, the combination of a receptacle for the soap to be dispensed, a revolvable dished cutter receiving the soap, a longitudinally movable plunger, a pair of oppositely directed tapered spiral springs between the top of said receptacle and said plunger, and a washer interposed between the adjacent ends of said springs.

4. In a soap dispensing machine, the combination of a receptacle for the soap to be dispensed, a revolvable dished cutter at the lower end of said receptacle, an axially disposed non-revolvable bar of angular section secured to the top of said receptacle, the lower end of said bar projecting part way into said dished cutter, for the purposes set forth.

In testimony whereof, I affix my signature.
IVAN J. NELSON.
